[57] CLAIM

The ornamental design for a bicycle storage rack, as shown and described.

DESCRIPTION

FIG. 1 is a right front perspective view of a bicycle storage rack showing my new design;

FIG. 2 is an elevational view of one side, the opposite side being a mirror image thereof;

FIG. 3 is a top plan view;

FIG. 4 is a bottom plan view;

FIG. 5 is a longitudinal sectional view taken on the line 5—5 in FIG. 3; and,

FIG. 6 is a median vertical sectional view taken on the line 6—6 in FIG. 2.
